G. T. IRWIN.
STANDARD ELECTRIC LAMP.
APPLICATION FILED MAY 22, 1919.

1,361,333.

Patented Dec. 7, 1920.

UNITED STATES PATENT OFFICE.

GEORGE THOMAS IRWIN, OF TORONTO, ONTARIO, CANADA.

STANDARD ELECTRIC LAMP.

1,361,383.

Specification of Letters Patent. Patented Dec. 7, 1920.

Application filed May 22, 1919. Serial No. 298,886.

To all whom it may concern:

Be it known that I, GEORGE THOMAS IRWIN, of the city of Toronto, in the county of York, in the Province of Ontario, Canada, have invented certain new and useful Improvements in Standard Electric Lamps, of which the following is the specification.

My invention relates to improvements in standard electric lamps, and the object of 10 the invention is to simplify, cheapen and otherwise improve the construction of the lamp and provide means whereby the lamp proper supported by the suspension means may be held definitely in position in relation 15 to the supporting arm and it consists essentially of the following arrangement and construction of parts as hereinafter more particularly explained.

Figure 1, represents a perspective view of 20 the upper portion of a lamp standard showing my device carried thereby.

Fig. 2, is an enlarged vertical section through the major portion of my device as indicated in Fig. 1.

Figs. 3 and 4 are details of the means for 25 holding the suspended lamp definitely in proper angular relation to its supporting arm.

In the drawings like characters of reference 30 indicate corresponding parts in the various figures.

1 indicates the standard proper, on the upper end of which is supported a cylindrical bearing member 2 having at its lower 35 end an annular flange 2^x adapted to be secured by screws or other suitable means to the upper end of the standard 1. The upper end of the cylindrical member 2 is provided with an externally threaded reduced portion 2' forming a shoulder 2². In the center of the reduced portion 2' is located an upwardly extending pin projection 2³. 3 indicates an internally threaded cap which is 40 screwed on to the external thread 2'. The top of the cap is provided with a central orifice 3^x.

4 indicates the main casting of the turnable structure by which the lamp is carried. The turnable structure 4 comprises 50 a rectangular body portion 4^x cuffed for the purpose of containing a wiring leading to the lamps. 4' indicates a depending member extending from the body 4^x and provided at its lower end with an orifice 4² and immediately below the body 4^x with a cross

orifice 4³. The pin projection 2³ hereinbefore referred to extends up into the orifice 4², the depending portion 4' extending through the orifice 3^x of the cap 3, the parts being held together by a projection 4⁴ extending diametrically from the depending portion 4' and bearing against the inner face of the upper portion of the cap 3. This projection 4⁴ may be formed by screws extending into the depending portion 4' or by any other suitable means.

From one face of the rectangular body 4^x extends a horizontal flange 4⁵ and from the opposite face of the body portion 4^x depends a hollow lug projection 4⁶, between the sides of which extends a bearing pin 4⁷ on which is mounted a roller 4⁸. 4⁹ indicates a pin depending from the flange 4⁵.

5 indicates a hollow member from the upper end of which extends the pin 4⁹ and on one side of which is a slotted opening 5' between the side of which extends a pin 5³ on which is mounted a roller 5⁴. Within the lower portion 7^x of the member 5 is journaled a pin 7² on which is mounted a roller 7¹.

8 indicates a tubular arm provided at its inner end with a solid head 8^x from which extend lugs 8', which lugs extend to the outside of the portion 7^x and are swung upon the ends of the pin 7². 9 indicates a tubular member surrounding the tubular arm 8 and slidably thereon. The outer end of the tubular member 9 is provided with a hollow annular bracket 9^x, the ends 9' and 9² being sleeve-like, the end 9' being secured around the tubular member 9 and the portion 9² directed downward for a purpose which will hereinafter appear. Between the sides of the member 9^x is secured a pin 9³ on which is mounted a roller 9⁴. 10 indicates a standard arm extending upwardly from the body portion 4^x and provided at its upper end with a horizontally directed portion 10^x provided with a forked end 10'. Between the sides of the forked end 10' is journaled a roller 10². From the opposite side of the body portion 4^x extends an upwardly directed standard 11, the intermediate portion 11^x of which is directed in an upwardly inclined direction, and the outer portion 11' in a horizontal direction. Between the inclined portion 11^x and the horizontal portion 11' depend lugs 11² between which is journaled a roller 11³. The extreme end of 110

the portion 11' is provided with an orifice 11⁴. 11⁵ indicates a ring extending through the orifice 11⁴. 12 indicates a counterweight provided at its upper end with a roller 12^x journalized on a pin 12' carried by the upper end of the weight. 13 indicates a chain secured at one end to the ring 11⁵ and depending down beneath the roller 12^x, then upward over the roller 11³ and then downward beneath the roller 4⁸, passing from the roller 4⁸ beneath the body portion 4^x and in frictional contact therewith through the orifice 4³ and over the roller 5⁴ from which it depends through the member 5 beneath the roller 7⁴ and then longitudinally through the inner tube 8 to the roller 9⁴ over which it passes, the free end of the chain depending through the sleeve-like portion 9² and forming a suspension means for the lamp proper which I will hereinafter describe.

14 indicates a ring extending around the tubular member 9. 15 indicates a chain which is also secured to the ring 14 and extends upwardly over the roller 10², a portion of the chain being provided with an enlargement or knot 15^x bearing against the fork 10' so as to limit the movement of the chain passing over the roller 10². Beneath the enlargement 15^x the chain is provided with a ring 15', the chain depending therefrom in slack form, the opposite end being looped up and connected to the base of the standard 10. Instead of employing the enlargement 15^x the chain may pass around a pin 15⁰ thereby supporting the arm 8. 16⁰ indicates a slit in the tube 9. 17⁰ indicates a projection extending from the arm 8 through the slit 16⁰, the projection having an inclined edge portion 16' terminating in a shoulder 16². The ring 14 normally rests upon the inclined portion 16' holding it out of frictional contact with the sleeve 9 and against the shoulder 16². The ring 14 is connected by a chain 16³ to a lug 9⁰ extending from the sleeve 9 for a purpose which will hereinafter appear, the ring 14 engaging the arm 8 between such projections.

16 indicates a lamp socket supporting a shade 17. The upper end of the socket is provided with a hooked arm 16^x extending at right angles to the socket. 18 indicates a hook secured to the lower end of the chain 13 forming the lamp suspension means. The hook 18 engages the hook arm 16^x when the lamp shade 17 is to be held in a normal horizontal position.

19 indicates a chain connected at one end to the extremity of the hooked arm 16^x and at the opposite end to the lower edge or bottom of the lamp shade 17.

When it is desired to tilt the lamp shade in an angular direction toward the position shown by dotted lines in Fig. 1 the hook arm 16^x is disengaged from the hook 18 and the chain 19 passed through the hook 18 to the

desired position for suspending the lamp, the chain 19 then depending in an angularly formed loop, one end secured to the arm 16^x and the other end to the edge of the lamp shade. 20 indicates the wiring of the lamp contained in the lamp shade 17 and carried by the socket 16. The wires 20 enter the socket through the lower portion of the hook arm 16^x and at their opposite end extend into the hollow body portion 4^x. 75

In order to hold the lamp and lamp shade 17 in a definite angular position in relation to the arm formed by the tubular members 8 and 9 I provide the lower end sleeve like portion 9² with diametrically arranged 80 notches 9⁰ into which the upper peripheral portion of the hook 18 fits, such notches being set in a parallel position to the arm 8. By inserting the hook in the notches as above described the lamp is held definitely 85 in position at right angles to the arm and to the position shown in the drawing.

It will, of course, be understood that a large shade is suitably supported by the standard 1 so as to extend over the whole 90 lamp. When the lamp is not in use the ring 15' is drawn down to engage the pin 15⁰. By the initial movement the arm 8 is swung up to a vertical position. The ring 14 then pulls on the chain 16³ drawing the outer portion 9 upward over the portion 8 and thereby carrying the lamp 17 up to be entirely hidden by the shade. 95

The tubular member 9 is provided with a perforation X and when drawn outwardly 100 so as to carry the perforation X in a line with the end of the tube 8, the weight of the lamp tends to slightly sag the tube 9 at its outer end so that the perforation X has a slight engagement with the end of the tube 105 8. If it were not for this arrangement, the weight of the lamp at one end of the chain would tend to pull the tube 9 inwardly upon the tube 8. By reason of the end of the tube 8 engaging in the perforation this is prevented. 110

What I claim as my invention is.

1. In an electric lamp, a supporting turnable body having an orifice extending therethrough, flexible lamp suspension means 115 passing through such orifice in contact with the upper wall thereof, an arm extending outwardly from the supporting body and carrying one end of the lamp suspension means, an arm extending outwardly from the 120 opposite side of the supporting body and carrying the opposite end of the lamp suspension means, and a counterweight connected to such opposite end.

2. In an electric lamp, a supporting turnable body having an orifice extending therethrough, a depending member carried at one side of the body, a standard extending upwardly from the opposite side of the body, a flexible lamp suspension means and suit- 125 130

ably located rollers adapted to guide the flexible lamp suspension means through the depending member and the orifice of the lamp supporting body.

- 5 3. In an electric lamp, a turnable supporting body having an orifice extending therethrough, a depending member carried at one side of the body, a standard extending upwardly from the opposite side of the body,
 10 a flexible lamp suspension means and suitably located rollers adapted to guide the flexible lamp suspension means through the depending member and through the orifice of the lamp supporting body to pass horizontally in frictional contact with a wall of
 15 said orifice, and counterweighting means carried by the opposite end of the flexible lamp supporting member.

4. In an electric lamp, a turnable supporting body, a depending member carried at one side of the body, a normally horizontal tubular arm swingably connected to the depending member, means for freely supporting the horizontal arm in a horizontal position and for raising the said arm upward and securing it in position, a lamp suspension means extending through the depending member and swing arm and adapted to carry a lamp at one end and a counterweight at
 20 the opposite end, and means frictionally bearing upon the flexible lamp suspension means intermediately of its length.

5. In an electric lamp, a turnable supporting body, a depending member carried by the supporting body at one side, a horizontal arm swung on the depending member, a tubular member carried by the horizontal arm, means for raising the arm to an angular position, and flexible lamp suspension means
 35 extending through such arm and depending member to the opposite side of the lamp supporting body, and a counterweight for the
 40

lamp carried by the opposite end of the lamp suspension means.

6. In an electric lamp, a turnable supporting body, a depending angular tubular member carried at one side of such body, a normally horizontal tubular arm swung upon the depending member and comprising an inner and outer tube telescopically connected together, means for raising the tubular arm to an angular position and telescopically extending the same, flexible lamp suspension means extending through such tubular members to the opposite side of the lamp supporting structure, and a counterweight for the lamp carried by the opposite end of the lamp suspension means.

7. In a lamp, a main support, a normally horizontal arm pivoted to said main support, a tubular member carried by said arm and slidably thereon, a flexible lamp suspension element having one end thereof passed through said arm and member to depend therefrom, and elevating means for the arm and member operable to initially swing said arm and member to a vertical position and to subsequently draw the member upwardly over the arm.

8. In a lamp, a main support, a normally horizontal arm swung upon the main support, a tubular member having a longitudinal slit carried by the arm and from which lamp suspension means is adapted to depend, a projecting portion depending from the arm through the slit and having a shoulder, and flexible means for raising the arm including an encircling ring engaging the shoulder.
